UNITED STATES PATENT OFFICE

2,225,705

CAR DOOR

John P. McWilliams, Cleveland, Ohio, assignor to
The Youngstown Steel Door Company, Cleve-
land, Ohio, a corporation of Ohio

Application July 23, 1938, Serial No. 220,892

2 Claims. (Cl. 16—99)

This invention relates to car doors and is direct-
ed more particularly to sliding car doors of the
lift type.

Car doors of the lift type are normally seated
frictionally upon supporting tracks. These doors
are provided with mechanism operable to elevate
the doors above the tracks and transfer their
weight to rolling means to secure easy movement
of the doors between open and closed positions.
The lifting mechanism utilizes members, usually
in the form of castings within which lifting de-
vices are housed, and a lever for actuating these
devices.

This invention has for an object the provision
of lift mechanism which shall effect reductions in
the number of parts employed, labor costs and
weight and a consequent simplicity and compact-
ness of construction and saving in cost.

A further object is to provide housing members
for lift mechanisms capable of association with
the actuating levers of these mechanisms to pre-
vent loss of the levers, serve as guides therefor
and resist outward pull on the levers tending to
bend them.

Other objects of the invention will become clear
as the description thereof proceeds. In the
drawing forming part of this specification:

Figure 1 is a fragmentary elevation of a car
door embodying the instant invention.

Figure 2 is a vertical section taken on line 2—2
of Figure 1.

Referring to the drawing, there is shown frag-
mentarily and for purposes of illustration a met-
alllic door 10 to which the invention is applied.
As illustrated, the door 10 is provided with hori-
zontal corrugations 11 and at its lower margin
carries a backing plate 12 and a reinforcing an-
gle 13, the vertically disposed leg 14 of this angle
being located between the backing plate 12 and
the lower margin of the door 10 while the hori-
zontally disposed leg 15 is directed outwardly.

Since the door 10 is of the lift type the hori-
zontal leg 15 of the bottom reinforcing angle 14
rests frictionally upon a supporting track 16 when
the door is in lowered position. The track 16 is
supported below the door opening by means of a
plurality of brackets, one of which is shown at
17. The track 16 is riveted to the brackets 17 as
indicated at 18 and in turn the brackets are se-
cured as by rivets 19 to the web 20 of a channel
shaped side sill 21. The track 16 is shown to be
angular in cross section and one of its flanges
22 extends downwardly.

With doors of the type illustrated mechanism
is provided to lift the doors so as to disengage the

horizontal flange 15 of the bottom reinforcing
angle 13 from the supporting track 16 and trans-
fer the weight of the doors to rolling means
whereby the doors may readily be moved to open
position. The particular lift mechanism illus-
trated embodies a roller 23 located adjacent the
lower forward corner of the door. The roller 23
is received within a roller retainer 24 and is car-
ried thereby by means of a pin or axle 25. The
roller retainer 24 is provided with oppositely ex-
tending trunnions 26 and 27, the latter of which
is journaled in a bearing provided in the upstand-
ing leg 14 of the bottom reinforcing angle 13
and in the backing plate 12. The roller retainer
24 is provided with an ear 28 which carries a stud 29.

The roller 23 and the roller retainer 24 are
housed within a member 30 preferably in the
form of a casting. The housing member includes
a hollow body portion 31 from the top and sides
of which an attaching flange 32 projects. The
side flanges 32 are shaped to conform to the lower
horizontal corrugation 11 formed in the door
10. The flanges 32 are adapted to be applied
to the door 10 and be riveted thereto as by means
of rivets 33 for the securement of the housing
member to the door. The body portion 31 of the
housing member is extended downwardly and
formed into an upwardly opening hook 34 adapt-
ed to cooperate with the depending vertical flange
22 of the track 16 to retain and guide the door
upon the track.

The trunnion 26 formed on the roller retainer
24 is journaled in a bearing 35 formed in the body
portion 31 of the housing member 30. The trun-
nion 26 as clearly shown in Figure 2 of the draw-
ing extends outwardly beyond the housing mem-
ber so as to be adapted to receive a lever 36 by
means of which the lift mechanism is actuated.
The projecting portion of the trunnion 26 is pro-
vided with flat vertical faces 37—37 and the por-
tion of the lever mounted upon the projecting
part of the trunnion is similarly conformed.

The housing member 30 is so formed as to
serve as a guide and retaining member for the
actuating lever 36. To this end, an arcuate flange
38 is provided on the body portion 31 of the
housing member. A cooperating member 39 sub-
stantially Z-shaped in vertical section is secured
to the inner face of the actuating lever 36 as by
means of a rivet 40. The depending flange 41
of the Z-shaped member 39 is offset relative to
the inner face of the actuating lever and is dis-
posed rearwardly of and in lateral relationship

to the arcuate flange 38 provided on the housing member 30.

The housing member 30 is constructed to limit the movement of the actuating lever 36. For this purpose the reinforcing ribs 42 and 43 terminate in the body portion of the housing member, thereby providing shoulders 44 and 45 which are aligned longitudinally with the actuating lever.

The foregoing description relates to the portion of the lift mechanism and to the housing member adjacent the lower forward corner of the door. It is to be understood that the remaining portion of the lift mechanism and its associated housing member are located adjacent the lower rear corner of the door. The construction of the considered portion of the lift mechanism and the housing member are essentially the same as the portion of the mechanism and housing member illustrated and herein described and no further description thereof is believed to be necessary.

The lift mechanisms adjacent the lower corners of the door are operated in unison by the actuation of the lever 36 in which, by virtue of the instant invention, a substantial reduction in size and weight has been effected. To this end a connecting bar 46 located within the lower horizontal corrugation 11 is provided. The bar 46 is flattened at its ends as indicated at 47 and is slipped over the adjacent studs 29 provided on the roller retainers. Simultaneous operation of the mechanisms is thus insured.

Elevation of the door is obtained by downward pull upon the lever 36 in a clockwise direction as viewed in Figure 1 of the drawing. Since the trunnions 26 and 27 are offset relative to the roller pin or axle 25, this movement of the operating lever will exert a force through the trunnions upon the door whereby the door will be

lifted from the track and supported upon the rollers. In this movement of the actuating lever it will be guided by the cooperating flanges 38 and 41 provided respectively on the housing member 30 and on the lever. These cooperating flanges, moreover, prevent loss of the lever and serve to resist any outward pull upon the lever which might tend to distort it. The downward movement of the lever is limited by its engagement with the shoulder 45.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. A housing member for enclosing a portion of a lift mechanism provided on a sliding lift door, said member comprising an attaching flange adapted for securing to a said door, a hollow body portion extending outwardly from said attaching flange and in which said portion of said lift mechanism is received and an arcuate guiding and retaining flange on said body portion, said arcuate flange being adapted to cooperate with means on an actuating lever of said lift mechanism for guiding and retaining said lever.

2. Lift mechanism for a sliding car door comprising a roller, an actuating lever, a housing member secured to said door having a hollow body portion for receiving said roller, an arcuate guiding and retaining flange on said body portion and means on said actuating lever cooperating with said arcuate flange for guiding and retaining said lever.

JOHN P. McWILLIAMS.
